(57) **CLAIM**

The ornamental design for a child seat for motor cars, as shown and described.

DESCRIPTION

FIG. 1 is the front perspective view of the child seat for motor cars;

FIG. 2 is a front view thereof;

FIG. 3 is a rear perspective view thereof;

FIG. 4 is a rear view thereof; and,

FIG. 5 is a side view thereof from the left side with the right side being a mirror image therewith.

The fragmented showing of the surface pattern on the straps is understood to repeat uniformly throughout the strap surfaces. The fragmented cross-hatching shown on the seat, seat back and headrest is understood to repeat uniformly throughout the circumscribed areas.
